DESIGN FOR A HOSE REEL

Earle S. Marsh, Temple City, Calif.

Application March 16, 1946, Serial No. 127,578

Term of patent 14 years

(CL. D91—1)

To all whom it may concern:

Be it known that I, Earle S. Marsh, a citizen of the United States, residing at Temple City, county of Los Angeles, and State of California, have invented a new, original, and ornamental Design for a Hose Reel, of which the following is a specification, reference being had to the accompanying drawing, forming part thereof.

Fig. 1 is a three-quarter side perspective view of the hose reel, showing my new design.

Fig. 2 is a side elevation thereof.

Fig. 3 is a rear view thereof.

I claim:

The ornamental design for a hose reel, substantially as shown.

EARLE S. MARSH.
